The ornamental design for an evaporator for volatile materials, as shown and described.

DESCRIPTION

FIG. 1 is a front view of an evaporator for volatile materials showing my new design;

FIG. 2 is a rear view thereof;

FIG. 3 is a top plan view thereof, the bottom being a mirror image of that shown;

FIG. 4 is a side view thereof, the opposite side being a mirror image of that shown;

FIG. 5 is a plan view in an alternative position; and,

FIG. 6 is a side view in the alternative position.

The broken-line showing of environmental structure in FIGS. 2-6 is for illustrative purposes only, and forms no part of the claimed design.

FIG. 1

FIG. 2

FIG. 3

FIG. 4

FIG. 5

FIG. 6
